UNITED STATES PATENT OFFICE.

EDWARD B. ALLEN, OF PORTLAND, MAINE, ASSIGNOR TO JAMES W. BROOKS,
TRUSTEE, OF CAMBRIDGE, MASSACHUSETTS.

MACHINE FOR MAKING FLEXIBLE NAIL-STRIPS.

SPECIFICATION forming part of Letters Patent No. 378,859, dated March 6, 1889.

Application filed March 10, 1887. Serial No. 230,369. (No model.)

To all whom it may concern:

Be it known that I, EDWARD B. ALLEN, of Portland, county of Cumberland, and State of Maine, have invented an Improvement in Machines for Making Nail-Strips, of which the following description, in connection with the accompanying drawings, is a specification, like letters on the drawings representing like parts.

10 This invention has for its object to produce a flexible strip or carrier for nails adapted for use in heel-loading, nailing, and other machines where separate nails are used, and the strip enabling the usual complicated feeding devices to be dispensed with.

My invention consists of a strip or band of paper or other flexible material having a series or row of slits or perforations near each edge, the said slits extending in the direction 20 of the length of the strip or band, and being placed opposite each other to receive in them the nails, the latter being retained in position transversely with relation to the strip or band.

The machine for making the flexible nail-receiving strip consists, essentially, of two die-blocks the meeting faces of which are provided with suitable cutting devices and bending or slit-opening devices, the former cutting the slits or perforations in the strip of material, while the latter open the said slits to receive the nails. Suitable means are also provided for moving the die-blocks toward or from each other, and also for feeding the strip of material forward.

35 Figure 1, in top view, shows a machine embodying my invention for making a flexible nail-receiving strip; Fig. 2, a vertical section of the machine shown in Fig. 1, taken on the dotted line xx ; Fig. 3, a plan view of the completed nail-receiving strip, and Fig. 4 a side view of the die-blocks.

The bed A, of suitable size and shape to support the working parts, has bolted to it two guide-frames, $a a'$, in which slide the die-blocks $a^2 a^3$. The bed has also bolted to it by bolts 23 two flanged bars, $b b'$, which form guideways for a working-bar, b^2 .

45 The die-block a^2 is provided with two cutting-blades, as c , (see Figs. 1 and 2), one above the other, and also with a tubular projection, as c^3 , and the die-block a^3 is provided with re-

cesses, as c^2 , (see dotted lines, Fig. 1,) to receive the cutting-blades $c c$, and with two tubular projections, c' . (See Fig. 4.) When the two die-blocks $a^2 a^3$ are brought together, the tubular projection c^3 enters between the two projections c' .

The two die-blocks are moved toward and from each other by two levers, $d d'$, pivotally connected at one end with the said blocks and crossing each other, the levers being pivoted on a stud, d^2 , rising from the bed A through a slot in the bar b^2 . The opposite ends of the levers $d d'$ are bent downward and provided with roller or other studs, as d^3 , which follow 65 in curved or cam slots $d^4 d^5$, cut in a working plate or bar, b^2 , moving upon the bed A between the guide-bars $b b'$.

It will be seen that by moving the working plate or bar b^2 toward or from the die-blocks 70 the levers $d d'$ will be moved on the pivot d^2 , and the die-blocks will be moved toward and from each other.

The working plate or bar b^2 may be moved by hand or in any other suitable manner.

75 The narrow strip or band e , of paper or other suitable flexible material, is fed between the die-blocks, where it is slit by the cutting-blades c , when it is fed forward one step, to be again slit. When being again slit by 80 the blades c , the material of the strip between the two slits first made by the cutting-blades will be acted upon by the tubular projection c^3 and be deflected into the space between the projections c' . When the strip is thus acted 85 upon by the die-blocks, a nail, tack, or equivalent is dropped or placed in the tubular projection c' , which is just above the projection c^3 , the said projections co-operating together to form bending or pressing devices for the strip, so 90 that the nail entering the tubular projections will also pass through the slots made in the strip of paper held open by the said projections.

95 The strip containing the nails is engaged by two clamps or jaws, $f f'$, pivoted to a stud, f^2 , fitting loosely in a slot, n , (see dotted lines,) cut in the working plate or bar, the outer ends of the said levers having friction-rolls, which follow in curved slots $f^3 f^4$, (shown by dotted 100 lines,) also cut in the working plate or bar, so that as the working-bar is moved toward and

from the die-block the clamps, jaws, or levers $f f'$ will be moved.

The slots $f^3 f^4$ are of such length that when the working plate or bar is moved toward the die-blocks one end of the slots will bear against the roller-studs carried by the levers $f f'$, and will force the said levers forward a short distance to engage the next nail of the strip, the stud f^2 moving in the slot n , and as the working plate or bar is withdrawn the opposite end of the slots $f^3 f^4$ will strike the friction-rolls or ends of the levers $f f'$, and cause the said levers to retreat from the die-blocks, thereby pulling the strip forward a distance equal to the space between the blades or tubular projections.

The strip containing the nails may be conveyed from the clamping jaws or levers, which in this instance constitute the feeding devices, 20 by any suitable means—such as rollers, (not shown;) or the strip may be wound upon a drum or cut in short lengths, if desired.

A flexible nail-receiving strip or carrier may thus be made of any suitable length with little 25 expense and with considerable speed.

I claim—

1. The combination, in a machine for making flexible nail-receiving strips, of the following instrumentalities, viz: two die-blocks, cutting-blades actuated thereby to slit the strip at intervals, oppositely-extended pressing or bending devices provided with nail-passages and adapted to act upon the opposite sides of the slit strip and bend it aside between the said slits 35 for the reception of a nail or fastening, and

means for moving the said die-blocks toward and from each other, substantially as described.

2. In a machine for making flexible nail-receiving strips, two die-blocks having cutting-blades to slit the strip, and bending or pressing devices for opening the said slits, combined with operating-levers, and a working plate or bar for moving the levers and die-blocks toward and from each other, substantially as described. 45

3. In a machine for making flexible nail-receiving strips, the die-blocks having cutting and bending devices for cutting and opening slits in the strip, combined with pivoted operating-levers for moving the die-blocks toward and from each other, pivoted clamping-levers for feeding the strip forward, and a working plate or bar for moving both the operating-levers and the clamping-levers, substantially as described. 55

4. In a machine for making flexible nail-receiving strips, the die-blocks having independent cutting and bending devices for cutting and opening opposite slits in the strip, the bending devices, including co-operating tubular projections on the said die-blocks, combined with strip-feeding devices, substantially as described. 60

In testimony whereof I have signed my name to this specification in the presence of two sub- 65 scribing witnesses.

EDWARD B. ALLEN.
